US0D1082664S

(12) **United States Design Patent** (10) Patent No.: **US D1,082,664 S**
(45) Date of Patent: ** Jul. 8, 2025

(54) **BATTERY CHARGER HOUSING**

(71) Applicant: **Suzhou Yihang Electronic Science and Technology Co., Ltd.**, Jiangsu (CN)

(72) Inventors: **Wei Yang**, Jiangsu (CN); **Tao Yang**, Jiangsu (CN); **Ning Ye**, Jiangsu (CN)

(**) Term: **15 Years**

(21) Appl. No.: **29/878,079**

(22) Filed: **Jun. 15, 2023**

(30) **Foreign Application Priority Data**

May 10, 2023 (CN) 202330270849.0

(51) LOC (15) Cl. **13-02**

(52) U.S. Cl.

USPC **D13/107**

(58) **Field of Classification Search**

CLAIM

The ornamental design for a battery charger housing, as shown and described.

DESCRIPTION

FIG. 1 is a front perspective view of a battery charger housing showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings depict portions of the battery charger housing and form no part of the claimed design.

1 Claim, 7 Drawing Sheets
